UNITED STATES PATENT OFFICE.

EARL C. POTTER, OF CHICAGO, ILLINOIS, ASSIGNOR TO THE SEFTON MANUFACTURING COMPANY, OF ANDERSON, INDIANA, A CORPORATION OF INDIANA.

SHIPPING BOX OR CARTON.

1,178,675.

Specification of Letters Patent. Patented Apr. 11, 1916.

Application filed January 3, 1916. Serial No. 69,961.

To all whom it may concern:

Be it known that I, EARL C. POTTER, a citizen of the United States, residing at Chicago, Cook county, Illinois, have invented certain new and useful Improvements in Shipping Boxes or Cartons, of which the following is a specification.

My invention relates to a container or carton constructed out of corrugated paper board, or material of like characteristics, and intended more particularly for the reception and protection of single bottles against shocks or rough handling, so that they may be safely shipped through the mails by parcels post, or transported by express, or in any other manner, without danger of breakage. With this end in view I have designed and constructed a new and useful box or carton, illustrated in the accompanying drawings and hereinafter described, and which constitutes an embodiment of my present invention in a preferred form, in which box I have attained a high degree of strength, and efficient protection of an enclosed bottle on all sides, without waste of stock and with consequent economy of manufacture.

My invention consists of various features of construction in the shape, disposition and arrangement of various members or parts of the box, the essential elements of which are more particularly pointed out in the appended claims.

Of the drawings Figure 1 is a perspective of the various blanks of which the carton is composed, partly folded and showing the manner in which they are grouped; Fig. 2 is a horizontal section on the line 2—2 of Fig. 3; Fig. 3 is a central vertical section on the line 3—3 of Fig. 2; Fig. 4 is a perspective of a folded box, with portions of some of the parts broken away, to show the position of underlying members of the box; Fig. 5 is a horizontal cross section of a modified construction, the plane of the view corresponding to that of Fig. 3; and Fig. 6 is a similar horizontal section, showing a filler inside the buffer member arranged to receive a number of tubes, either of glass, or of other material which requires protection.

The same reference characters indicate the same parts in the several views.

In the specific form of package herein

illustrated and described, four side walls, 55 1, 2, 3, and 4, formed of a single rectangular blank creased transversely of its length and folded to form a rectangular tube—the meeting ends of the blank along one edge of the tube being suitably connected, as by a cloth 60 hinge strip,—constitute an outer shell A, within which are arranged the remaining parts of the box. These inner parts comprise two lining members, and an inner 65 spacing and buffer member. The outer lining member B consists of a rectangular strip transversely folded to form an outer bottom or end wall 5, a side flap 6, an inner side wall 7, an upper top or end wall or cover 8, and a side flap 9 which is complementary to the 70 side flap 6 and together with it constitutes a side wall opposite the wall 7. The inner lining member C also consists of a rectangular strip transversely folded, and includes an inner bottom wall 10, a side wall 11, and 75 an inner top or cover wall 12. The spacing and buffer member D, like those before described, is folded from a rectangular blank scored on transverse lines, and comprises four walls, 13, 14, 15 and 16, of equal width, 80 and two spacing wings, 17 and 18, also of the same width as each other, at the opposite end of the blank; and the size of the walls and the attached wings is such that the blank may be folded together to form a 85 square tube with the wings extending from one of its corners or edges in a plane lying at an angle of 45° from the sides forming the corner, and the tube and wings may be arranged to snugly fit within the lining 90 members B and C, and the shell A in the assembled box, as hereinafter explained.

As will be readily understood from the drawings, the outer lining member B is arranged within the outer shell A, with its 95 bottom wall 5 flush with the bottom edge of the shell, and its side flap 6 and side wall 7 in contact with opposite side walls of the shell. The inner lining member C is arranged with its bottom wall 10 in contact 100 with the bottom wall 5 of the member B, and its side wall 11 contiguous with one of the remaining side walls of the shell A; and the buffer member is arranged centrally 105 of the carton with the sides 13, 14, 15 and 16 extending at an angle of 45° from the inclosing side wall members, and with the wings 17 and 18 lying opposite the wall 11.

and together constituting an inner side wall coextensive with the contiguous wall of the shell A.

In closing the package, assuming the top 5 end walls to be open and the bottle to have been inserted, the end wall 12 of the inner lining member C is first folded down, and the outer top wall 8 of the member B is then folded down over it, the side flap 9 being 10 tucked between the members A and D. A stout cord or tape may then be tied around the package to prevent disengagement of the parts, or other suitable retaining means used for the purpose.

15 In Fig. 5 I have shown a slightly modified form of carton, in which an oblong buffer is arranged within a square outer shell and lining members to receive an oval flask or bottle. The wings 17^a and 18^a of 20 the buffer member are in this case of different widths, the exact proportions in any given case of course depending on the shape of the bottle to be accommodated.

In Fig. 6 a filler 19 is employed to adapt 25 the package for carrying a number of glass tubes, or tubular bottles, or articles of similar shape, as, for instance, collapsible tubes containing any sort of pasty material which it is desired to ship carefully protected.

30 If desired, the carton of course may be made of such dimensions that buffers may be inserted at its top and bottom, or the top and bottom wall may be provided with integral or attached buffer elements, but in 35 practice it is found that sufficient protection is afforded by the construction above described. The greatest liability to breakage incident to shipment by parcels post is due to blows of postmarking hammers used by 40 post office employees, and since the package is always addressed and stamped on its side, the sides of the box require the greatest protection.

45 It is manifest that my improved container may be used for the shipment of square bottles, or rectangular bottles, as well as bottles having a curved perimeter but if the bottle completely fills the buffer member to its corners, its edges will not be so well protected as its sides. My package is therefore 50 designed and particularly well adapted for bottles of such shape that more or less space will be left at the corners of the buffer member, in which case the fullest protection will 55 be attained.

I claim:

1. A shipping box comprising a four-sided outer shell, an outer lining member including a bottom wall, opposite side walls and a top hinged to one side wall; an inner 60 lining member including a bottom wall, one side wall and a top; and a buffer member including four diagonal inside walls and two wing members together forming an inner side wall opposite said last-mentioned 65 side wall.

2. A shipping box comprising a four-sided outer shell; an outer lining member including a bottom wall, a side flap, a side wall, a top hinged to said side wall, and a 70 second side flap hinged to said top; an inner lining member including a bottom wall, one side wall and a top; and a buffer member including four diagonal inside walls and two wing members together forming an 75 inner side wall opposite said last-mentioned side wall.

3. A shipping box comprising a four-sided outer shell; an outer lining member including a bottom wall, opposite side walls 80 and a top hinged to one side wall; an inner lining member including a bottom wall, one side wall and a top; and a buffer member including four diagonal inside walls and two wing members arranged opposite said 85 last-mentioned side wall and extending to the opposite side walls of said outer lining member.

4. A shipping box comprising a four-sided outer shell; lining members including 90 bottom and top walls and three inner side walls; and a buffer member including four diagonal inside walls and two wing members coextensive with one contiguous wall of the shell and together constituting a fourth 95 inside side wall.

5. A shipping box comprising a four-sided outer shell; lining members including a plurality of bottom walls, and a plurality of top walls and three inner side walls; and 100 a buffer member including four diagonal inside walls and two wing members coextensive with one contiguous wall of the shell and together constituting a fourth inner side wall.

EARL C. POTTER.
